MAGNETIC TAPE TRANSPORT OR THE LIKE

Robert M. Hofland, Boulder, and Jack W. Stringer,
Hygiene, Colo., assignors to International Business
Machines Corporation, Armonk, N.Y.

Filed June 8, 1971, Ser. No. 151,023

Term of patent 14 years

Int. Cl. D14—01

U.S. Cl. D26—5 C

FIG. 1

FIG. 2

FIG. 3

FIG. 4

FIG. 5

FIG. 1 is a front perspective view of a magnetic tape transport, with the tambour in an open position;

FIG. 2 is a front perspective view of a second modified embodiment of the tape transport illustrated in FIG. 1, with the transparent tambour in a closed position;

FIG. 3 is a front perspective of the tape transport illustrated in FIG. 1 with the tambour in a closed position;

FIG. 4 is a front perspective of a third modified embodiment of the tape transport illustrated in FIG. 1; and

FIG. 5 is a front perspective of a fourth modified embodiment of the tape transport illustrated in FIG. 1 with a transparent vacuum column cover.

The undisclosed rear portions of the tape transport are unornamented, and the broken lines are shown for illustrative purposes only.

We claim:

The ornamental design for a magnetic tape transport or the like, substantially as shown and described.
